UNITED STATES PATENT OFFICE.

MONTRAVILLE P. MIGHELL, OF NEW YORK, N. Y.

FARM GATE.

Application filed October 20, 1922. Serial No. 595,713.

This invention relates to improvements in farm gates and its purpose is to provide an improved gate particularly adapted for use on the farm to permit wagons and other vehicles to pass through the gate opening and having also embodied therein a smaller gate adapted to permit the passage of pedestrians, horsemen, and the like. An important object of the invention is to provide a gate of simple and rugged construction which may be readily mounted in place and which will maintain its proper balanced position after long continued use. A further important object is to provide an improved means of mounting the gate on its support so that the sagging of the gate is prevented and a free swinging movement thereof permitted at all times.

Other objects and advantages of the invention will appear more fully from the following specification taken with the accompanying drawings in which one embodiment is illustrated.

In the drawings Fig. 1 shows a side elevation of a section of a fence having the improved gate embodied therein, a portion of the fence being broken away. Fig. 2 shows a detailed sectional view on the line 2—2 of Fig. 1 looking in the direction of the arrows. Fig. 3 shows a vertical section through the cup-shaped member which supports the post at the pivotal end of the gate. Fig. 4 shows a perspective view of a slidable member by which the smaller gate is secured in its normal position. Fig. 5 is a perspective view showing the spring latch member by which the large gate is secured in its closed position, and Fig. 6 is a detailed sectional view on the line 6—6 of Fig. 1 looking in the direction of the arrows.

As illustrated in the drawings a farm gate 10, having a small gate 11 embodied therein, is shown closing the gate opening which is formed in a woven wire fence 12. The gate 10 comprises a lower horizontal frame member 13, an upper horizontal frame member 14 and an upper inclined frame member 15 which are connected by the vertical posts or frame members 16, 17, 18 and 19. All of these frame members are preferably in the form of iron or steel rods or pipes and they are connected together by suitable T-connections 20, cross-couplings 21 and elbows 22 as shown in the drawing. A sheet of woven wire netting 25 extends between the lower frame member 13 and the upper horizontal

frame member 14 and between the vertical frame members 17 and 19, being secured to the frame members by any suitable fastening means.

The small gate 11 comprises a lower horizontal frame member 28, an upper horizontal frame member 29, an upper arch-shaped frame member 30 and a pair of vertical side frame members 31 which are secured together by T-connections and elbows, as in the construction of the larger gate. The small gate 11 is supported on the vertical frame member 16 at the large end of the gate 10 by means of clamping devices 33, having the form shown particularly in Fig. 6, where the device is illustrated as comprising a pair of clamping plates 33^a secured together by a cap screw 34. The ends of the plates 33^a are provided with recesses which are adapted to receive the frame members 16 and 31 and when the clamping devices are applied as shown in Fig. 1, the upper device 33 is adapted to rest on a fixed collar 35 which is secured to the post 16. Each clamping device is adapted to form a rigid connection with one of the frame members while permitting a free turning movement of the other frame member to which it is connected and it is preferred to have the clamping devices rigidly engage the post 31 while having a free turning movement on the post 16. The T-connection at the end of the cross member 29 of the small gate is adapted to rest on the upper side of the upper clamping device 33 so that the small gate is supported on the clamping members without depending entirely on the frictional grip exerted by the plates 33^a. For the purpose of securing the small gate 11 in its closed position, any suitable fastening device may be employed, the preferred device illustrated in the drawings comprising a sleeve 37 which is slidably mounted on the upper horizontal frame member 29 and arranged to be moved thereon by means of a handle 38. An arm 39 inclines downwardly from the sleeve 37 and carries a pair of projecting flanges 40 which are adapted to pass on opposite sides of the vertical frame member 31 of the small gate 10 and also on opposite sides of the vertical frame member 17 of the large gate.

Instead of employing the usual hinges for connecting the large gate to its support, an improved construction has been provided comprising a metal bearing member 45 of cup-shaped form which is adapted to be sup-

ported near the base of the fence post 46, adjacent to the large end of the gate. In practice the base of the post 46 as well as the bearing member 45 are preferably embedded in concrete 47. The bearing member 45 is adapted to receive the lower extremity of the frame member 16 at the large end of the gate 10, which extremity may be of rounded or spherical form in order to provide a smooth bearing during the turning of the gate. Near the upper part of the gate a post 16 engages an eye-bolt 48 which extends through the post 46 and is secured in position by a nut 49, the post 16 being permitted to turn freely within the eye-bolt while the weight of the gate is supported firmly by the bearing member 45 at the bottom of the post. A collar 50 having a hook 51 carried thereby is rotatively mounted on the upper extremity of the post 16 above the T-connection by which this frame member is connected to the upper inclined frame member 15. A tie-rod 52 is connected at one end to the hook 51 and at its other end to the base of the next adjacent post 53 in the fence 12 so that the weight of the gate 10 is supported in part by this tie-rod. A turn-buckle 54 is preferably provided for connecting the two sections of the tie-rod 52 so that the effective length of the rod may be adjusted to regulate the position of the frame member 16 in its bearings and thereby insure a free swinging movement of the gate. The gate is adapted to be secured in its closed position by means of a latch member 55 which is secured to the fence post 56 adjacent to the small end of the gate by means of a bolt 57. This latch member carries parallel flanges 58 at its upper end which are adapted to pass on opposite sides of the vertical frame member 19 of the gate, and one of these flanges is preferably provided with a projecting flange 59 which may be engaged by the operator to push the latch member toward the post and thereby release the gate.

The improved trussed construction of the gate is adapted to maintain the frame of the gate in its original form without sagging and the free movement of the gate is further insured by the improved method of mounting it without the use of the usual hinges, since the weight of the gate is supported chiefly by the thrust bearing at the lower end of the frame member 16 while the tendency of the gate to tilt away from the post 46 is restricted effectively by the tie-rod 52 connected to the next post of the fence. The strain of supporting the gate is thus distributed between two posts of the fence and the turning moment exerted by the gate is applied chiefly to the base portion of the post 53 so that there is substantially no tendency for either of the posts 46 or 53 to become tilted in the direction of the gate

opening. In addition to these important advantages, the invention is of greater convenience and utility because of the embodiment therein of the small gate 11 which may be used by persons on foot or on horseback, the incline of the upper frame member 15 providing sufficient space at the large end of the gate for this purpose.

Although one form of the gate has been shown and described for purposes of illustration it will be understood that the invention may take various other forms without departing from the scope of the appended claims.

I claim:

1. A gate comprising rigidly interconnected horizontal and vertical frame members, and means for rotatably supporting one of the end vertical members of the gate adjacent a fence post for maintaining the gate in operative position, said supporting means comprising a fixed member engaging the lower portion of said vertical member, and anchoring means independent of said post in connection with the upper portion of said vertical member.

2. A gate comprising rigidly interconnected horizontal and vertical frame members, one of the end vertical members being extended below and above said horizontal members, and means for rotatably supporting each end of said extended vertical member adjacent a fence post for maintaining the gate in operative position, said supporting means each including ground engaging means independent of each other and of the post.

3. A gate comprising rigidly interconnected horizontal and vertical frame members, one of the end vertical members being extended below the bottom horizontal member, and means for rotatably supporting said extended vertical member adjacent a fence post for maintaining the gate in operative position, said supporting means comprising a step bearing for the foot of said end vertical member, a member vertically spaced from said bearing and engaging said end vertical member, and ground engaging means in connection with said vertically spaced member and independent of said bearing and said post.

4. A gate comprising rigidly interconnected horizontal and vertical frame members, one of the end vertical members being extended upwardly and downwardly beyond said horizontal members, means for rotatably supporting each end of said extended vertical member adjacent a fence post for maintaining the gate in operative position, said supporting means comprising a step bearing for the foot of said extended member, a swivel member at the top of said extended member, a tie member connected at its one end to said swivel member and to

anchoring means independent of said post at its other end, and guide means fixed to said post and engaging said extended vertical member below said swivel member.

5. A gate comprising rigidly interconnected horizontal and vertical frame members, means for rotatably supporting one of the end vertical members for maintaining the gate in operative position, and an auxiliary gate disposed within the main gate adjacent said end vertical member and pivoted to the latter.

10. A gate comprising rigidly interconnected horizontal and vertical frame members, and means for rotatably supporting one of the end vertical members of the gate adjacent a fence post for maintaining the gate in operative position, said supporting means comprising a fixed member engaging the

lower portion of said vertical member, 20 anchoring means independent of said post in connection with the upper portion of said vertical member, and an auxiliary gate disposed within the main gate adjacent said end vertical member and pivotally connected 25 to the latter.

15. A gate comprising a horizontal bottom member and inclined top member and vertical members rigidly connecting the ends of said longitudinal and inclined members, the 30 longer of said vertical members being rotatably supported for maintaining the gate in operative position, and an auxiliary gate disposed within the main gate adjacent said last named vertical member and pivoted 35 thereto.

MONTRAVILLE P. MIGHELL.
